R. F. GREENE

BUILDING BLOCK AND WALL CONSTRUCTION

Filed Dec. 24, 1924

Inventor:
Robert F. Greene,
by Justin H. Gearing.
Attorney.

UNITED STATES PATENT OFFICE.

ROBERT F. GREENE, OF WABAN, MASSACHUSETTS.

BUILDING BLOCK AND WALL CONSTRUCTION.

Application filed December 24, 1924. Serial No. 757,863.

My invention relates to building blocks, particularly hollow tile blocks, and to wall construction in which these blocks are used.

Heretofore walls made of blocks, have been designed in various ways to resist the transmission of heat and moisture. In general, these walls and blocks have been objectionable or impractical owing to their excessive cost, complicated structure, mechanical weakness, excessive weight of the blocks, difficulty in assembling and aligning the blocks, or because of other difficulties.

One object of the present invention is to overcome the above difficulties and to provide a wall which efficiently resists the transmission of heat and moisture.

Another object is to provide blocks, especially hollow tile blocks, of low cost and of suitable form and strength, adapted to be easily and quickly assembled with other blocks or bricks for producing a wall of the kind referred to.

In accordance with the present invention, a wall constructed of blocks is provided with ducts or air spaces along the seams between adjacent superposed blocks. These spaces are provided by V-shaped channels in one or both of the two load bearing sides between adjacent superposed blocks, the channels providing with respect to the bearing faces of the blocks, air spaces of substantially triangular cross section. The location, form, and cross sectional area of these air spaces are such as to increase the heat insulation of the wall, to resist the transmission of moisture through the wall and to provide a block of maximum strength. This form of construction is particularly applicable to hollow tile blocks.

One side wall of each channel defines a plane, preferably normal to the adjacent bearing side to serve as a reenforcement for the block along the side of an air space therein. When a channel is provided in both bearing sides of a block, one side wall of each channel defines the same plane, these side walls being extended to form a flat web directly connecting the vertices of the channels. The two channels are preferably disposed at opposite sides of this plane, and the web thus divides the blocks into two symmetrical sections. The symmetry of this form of block permits it to be placed on either bearing side with equivalent effect and so simplifies the construction of walls. By disposing each channel so that it un-

equally divides the corresponding bearing sides of the blocks, it will be seen that the reenforcing web between the channels may be disposed centrally in the block to interconnect central points in the two bearing sides of the block.

The blocks of the present invention are particularly adapted for use as a backing wall for a brick facing consisting of ordinary courses and header courses, certain of the blocks being offset to interlock with the header courses.

These and other objects and features of the invention will be understood more clearly in view of the following description and the accompanying drawing, in which:

Fig. 1 is a perspective view partly in section of a wall, and

Fig. 2 is a perspective view of an offset block.

In Fig. 1, the wall 1 includes the brick facing 2 backed by the superposed blocks 3, 4 which may be solid or may be provided with parallel longitudinal hollow spaces or ducts, as shown. The blocks are preferably so positioned that the air spaces therein and the seams between the load bearing sides of the blocks are disposed horizontally. The hollow forms are conveniently made as tiles. The opposite sides of any given block are preferably parallel to each other.

Block 4 is preferably offset so that a space is provided between block 3 and the thin end 5 of block 4. The header courses 6 of the brick facing extend rearwardly between blocks 3 and 4 and interlock therewith. The difference in height between the two ends of block 4 is preferably equal to the thickness of a header course.

It is to be understood that the wall 1 may be extended indefinitely in vertical directions in the manner shown, that is, by adding alternately a block 4 and a block 3 to those shown, and adding brick facing to match the blocks in the manner shown.

A channel 7 in each of the opposite bearing sides of blocks 3, and a channel 8 in one of the bearing sides of blocks 4, are of V-shaped cross section and extend longitudinally of the blocks and wall, being parallel to the air spaces in the blocks. Each channel forms with respect to the adjacent bearing side of the block, a duct or air space of substantially triangular cross section. One side wall 9 of channel 8 is extended as a flat web or wall 10 to the opposite bearing side

of the block and forms a side wall for the thicker portion of the block. Wall 9, 10 preferably defines a plane normal to the bearing sides of the block and in this position provides maximum reenforcement for the load bearing sides of the block.

In each block 3, the side wall 11 of one channel 7 is connected directly with the side wall 11 of the other channel by means of a reenforcing web 12. Side walls 11 and web 12 preferably define the same plane normal to the bearing sides of the block. By placing the channels 7 of any one block at opposite sides of web 12, the block retains such symmetry that it may be placed on either bearing side with equivalent effect.

The reenforcing web 13 interconnects web 12 with the walls of the block 3 between its bearing sides at points substantially midway between the bearing sides. Block 3 is shown as being equal in height with four courses of bricks, but it may be of greater or less height, and is preferably of a height which is an integral multiple of the thickness of one course of bricks. If desired, web 13 may be omitted, especially when block 3 is of less height than that shown. It will be noted that blocks 3 and 4 are so positioned that webs 10 and 12 of the superposed blocks are in alignment with each other in the plane defined by one of the side walls of each channel 7 or 8, the wall being thus reinforced from top to bottom by the direct support furnished by these webs acting in a vertical plane.

When cement such as mortar is used in the seams of the wall, channels 7 and 8 are left substantially free of mortar. The mortar is preferably completely interrupted by an air space where channels 7 or 8 register with a seam. The mortar is also preferably omitted from the upper half of the vertical seam between blocks 4 and header bricks 6, the resulting air space communicating with the air space 7 above it. Channel 8, in registering with channel 7 of the block 3 below, forms a combined air space of triangular cross section. It will be noted that each brick in the facing is mortared to the backing.

The air spaces provided by channels 7 and 8 tend to collect water or moisture which enter the wall at any one point through the seams and tend to diffuse the water or moisture by evaporation, or otherwise, so that it is prevented from passing completely through the walls. These channels also increase the heat insulating characteristics of the wall by increasing the number of closed air spaces in the wall. The amount of material used in the blocks and the resulting wall is a minimum for the number of air spaces provided and for the resulting strength of wall. Prior forms of blocks and walls require larger amounts of

material and are of greater weight than is required by the present invention to obtain the desired results.

If desired, channels 7 and 8 may be employed as conduits for various purposes, an advantage being that pipe, wires, etc., may be simply laid in place in the channels while the wall is being constructed, without "fishing" through the conduits.

It is to be understood that the principles of my invention are capable of wide application, and that the invention is not to be limited to the specific modifications illustrated and described herein, by way of example. Various modifications of the invention will be apparent to one skilled in the art. Features of my invention, believed to be patentable, are set forth in the appended claims.

I claim:

1. A hollow building block having two bearing sides, a channel dividing each of said sides, each of said channels having two side walls disposed at an angle with respect to each other to form a V, and a flat web connecting the bearing sides of said block, said web constituting one of the side walls for each of said channels. 85
2. A hollow building block having two bearing sides, a channel of V-shaped cross section dividing each of said sides unequally, and a web directly connecting the vertices of said channels. 95
3. A hollow building block having two bearing sides, a channel of V-shaped cross section dividing each of said sides unequally, and a web directly connecting the vertices of said channels, said web dividing the block into two symmetrical sections. 100
4. A hollow building block having two bearing sides, a channel dividing each of said sides, one side wall of each of said channels defining the same plane, said channels being disposed on opposite sides of said plane, and a flat web connecting said side walls. 105
5. A hollow building block having two bearing sides, a channel dividing each of said sides, one side wall of each of said channels defining the same plane, said channels being disposed on opposite sides of said plane, a flat web connecting said side walls, and another web interconnecting said first mentioned web and the walls of the block between said bearing sides at points substantially midway between said sides. 115
6. In a wall construction, a brick facing having a plurality of ordinary courses and a bonding course between said ordinary courses, a backing of blocks having horizontal seams therebetween and having horizontally disposed air spaces extending therethrough, said bonding course being interlocked with said blocks, each of the bricks in said facing being mortared to said back- 125

130

ing, and a channel dividing one of the bearing sides of each of said blocks and providing an air space extending along the seam at said bearing side parallel with the air spaces through said blocks, each of said channels having two sides disposed at an angle with respect to each other to form a V, one of said sides being normal to the corresponding bearing side of the block and

extending directly to the opposite bearing side of the block, said extending sides being in alignment with each other whereby a direct line of vertical support is provided through said wall.

In witness whereof, I here subscribe my name this 22nd day of December, 1924.

ROBERT F. GREENE.
